UNITED STATES PATENT OFFICE.

THOMAS J. POTTER, OF LOS ANGELES, CALIFORNIA.

GAS-RADIATOR.

1,368,571.

Specification of Letters Patent. Patented Feb. 15, 1921.

Application filed December 3, 1919. Serial No. 342,248.

To all whom it may concern:

Be it known that I, THOMAS J. POTTER, a citizen of the United States, residing at Los Angeles, in the county of Los Angeles and

5 State of California, have invented a new and useful Improvement Comprising Gas-Radiators, of which the following is a specification.

10 My invention relates to gas radiators, that is to say, radiators which have the general form and appearance of steam radiators, but which are provided with a gas jet so that they are self-contained.

15 I have found in practice that it is extremely difficult to design any form of gas radiator which can be operated satisfactorily under a wide variation in flue conditions. Such devices are often installed using very small and insufficient flues, and at other times it is necessary to connect them into chimneys which produce a very strong draft. There is also a great difference in the draft produced in any particular chimney under widely different conditions. In first starting up any sort of a heating appliance on a cold 20 chimney the draft produced is quite feeble and considerable difficulty is often experienced in getting gas appliances to operate under these conditions. On the other hand, after the gas appliance has been working for a short time the flue becomes heated and a strong draft is produced. Where the draft is feeble it is difficult to prevent the heating appliance from being smothered due to insufficient draft, and where there is a very 25 strong draft many types of heating devices are inefficient due to the fact that large quantities of air in excess of the amount required for combustion are drawn through the heating device, thus tending to abstract heat 30 therefrom, this heat going up the chimney in the form of heated gases.

An object of my invention is to provide a radiator having a self-contained flue in each section of unit, in which the draft will 45 be very quickly established and which will maintain a uniform circulation of air through the radiator largely independent of the draft of the chimney, and to which the radiator is connected.

50 A further object of the invention is to provide means for admitting air directly into the main flue so that when the flue tends to produce an excessive draft that this condition will be relieved by the direct admission 55 of air to the flue, which air is not passed

through the radiator and which does not therefore tend to decrease the efficiency of the radiator by the passage of air therethrough.

A still further object of the invention is to 60 provide means in connection with the gas radiator for supplying air continuously to the flue when the radiator is not in operation. I have found that there is a strong tendency for moisture to collect in flues and that it is 65 extremely hard to start a gas radiator on a moist flue. I therefore provide means in my radiator for maintaining a circulation of air through the flue after the fire in the radiator is extinguished, this circulation clearing the 70 flue of any gases which might be contained therein which would tend to condense, and at the same time removing from the flue by evaporation any moisture which may be contained therein.

75 Further objects and advantages will be made evident hereinafter.

Referring to the drawings which are for illustrative purposes only,

Figure 1 is a perspective view of a radiator embodying my invention.

Fig. 2 is a section through one of the heating units of the radiator.

Fig. 3 is a section through the vent unit of the radiator; and,

Fig. 4 is a section on a reduced scale showing an alternative form of heating unit.

85 In practice, I prefer to make my radiator of an odd number of units, the central unit 11, hereinafter designated as the vent unit, 90 being placed in the center of certain other units 12, hereinafter referred to as heating units. Extending longitudinally through openings 13 is a gas burner 14. Each of the heating units 12 is provided with an air inlet 95 opening 15 in the bottom thereof, this opening being below the burner 14 and the interior of the unit being open so that the products of combustion can pass upwardly from what may be termed the primary or 100 combustion chamber 16 through passages 17, 18 and 19 into what may be termed the secondary or expansion chamber 22. The passages 17, 18 and 19 are of very much smaller cross-section than the combustion chamber 16 and deliver the products of combustion over a pocket 20. The expansion chambers 105 22 are connected together through openings 23, these openings delivering the hot gases toward the center of the radiator, the vent 110

section 11 being also provided with openings 23 on either side through which these hot gases flow into an upper chamber 24. The bottom of this chamber is formed by a shelf 5 25 with a space forming an opening 26 at one side thereof and a second shelf 27 is placed below this opening, a vent 28 being provided between the shelves as shown in Fig. 3.

10 The burner 14 is inclosed in a housing 29 where it passes through the section 11 so that the products of combustion can only enter the section 11 through the opening 23. A starting opening 30 is provided near the 15 bottom of the section 11.

In some cases I have found it desirable to make the radiator in the form shown in Fig. 4, which shows a heating section, the siphon being formed of passages 31 and 32 20 located in one side of the radiator.

The method of operation of my invention is as follows:

The burner being lighted through the opening closed by a cover 35 in one end of 25 the radiator, the products of combustion soon fill the combustion chambers 16 and pass through the passages 17, 18 and 19 into the expansion chambers 22. By making these passages of relatively small area I am 30 able to get a high velocity and to prevent the products of combustion from seeping back into the combustion chambers. Any condensation settles in the pockets 20 which are adjacent to the burner 14 so that they 35 are heated by direct heat from the burner, thus revaporizing the condensation so that it can be carried off with the other products of combustion through the openings 23. The products of combustion being delivered 40 through the openings 23 into the chamber 24 they flow through the opening 26, being taken off by the vent 28.

It will be noted that the passage 17 provides a self-contained draft means which is 45 of very great value in starting as it is very quickly heated and the draft is instantly established.

It will be further noted that the passages 17, 18 and 19 are so arranged that any gases 50 of combustion which are passed over the bend therein cannot return to the combustion chamber and smother out the fire. It should be further noted that the vent 28 is placed next to the wall so that the heated 55 portion of the siphon is away from the wall and toward the room, which is the space to be heated. As a result the front portion of the radiator reaches the desired temperature almost at once and begins radiating heat 60 into the room without the necessity of waiting to heat all of the material in the radiator.

It should further be noted that the combustion chamber 29 in the vent section is 65 heated as soon as the burner is lighted and

that this heated section heats the air in the lower portion of the vent section, which air immediately starts a draft through the vent 28, the air for this draft being supplied through the opening 30. This lower draft 70 is started almost at once after the radiator is lighted.

It should be further noted that after the radiator has been operating for some time and the fire shut off therein that the natural draft of the hot flue directs air through the opening 30 thus clearing the flue of any gases which might condense, and thoroughly drying out the flue by evaporating therefrom any moisture contained therein. 80 The opening 30 is also of great value in ventilating the room, air being taken constantly therethrough, this air being taken off close to the floor at which point the cold air containing most of the impurities tends to 85 settle.

I claim as my invention:—

1. In a gas radiator, the combination of walls forming a combustion chamber; means for producing hot gases of combustion in 90 said chamber; walls forming an expansion chamber; means for withdrawing hot gases from said expansion chamber; and walls forming an inverted U-shaped passage between said combustion and expansion chambers. 95

2. In a gas radiator the combination of walls forming an upper chamber; means for introducing heated gases of combustion into said chamber; walls forming a lower 100 chamber, the wall between said chambers having a space forming an opening therein; a vent pipe leading out of said lower chamber, the walls of said lower chamber having a starting opening therethrough below said 105 vent pipe; and a shelf between said starting opening and said vent pipe.

3. In a gas radiator, the combination of walls forming a combustion chamber, a gas burner delivering its products of combustion 110 into said combustion chamber, walls forming an expansion chamber above said combustion chamber, means for withdrawing said products of combustion from said expansion chamber, and walls forming an 115 inverted U-shaped passage extending from the top of said combustion chamber up one side, across the top, and down the other side of said expansion chamber and delivering said products of combustion to the lower 120 portion of said expansion chamber.

4. In a gas radiator, the combination of walls forming a combustion chamber, a gas burner delivering its products of combustion into said combustion chamber, walls 125 forming an expansion chamber above said combustion chamber, walls forming an exit opening in one side of said expansion chamber near the top thereof, and walls forming an inverted U-shaped passage extending 130

from the top of said combustion chamber up one side, across the top, and down the other side of said expansion chamber and delivering said products of combustion to the lower 5 portion of said expansion chamber.

5. In a gas radiator, the combination of walls forming a combustion chamber, a gas burner delivering its products of combustion into said combustion chamber, walls 10 forming an expansion chamber above said combustion chamber, walls forming a pocket in open communication with said expansion chamber, said pocket being so placed that said walls are heated by said burner, means 15 for withdrawing said products of combustion from said expansion chamber, and walls forming an inverted U-shaped passage extending from the top of said combustion chamber up one side, across the top, and 20 down the other side of said expansion chamber and delivering said products of combustion to the lower portion of said expansion chamber.

6. In a gas radiator, the combination of walls forming a combustion chamber, a gas 25 burner delivering its products of combustion into said combustion chamber, walls forming an expansion chamber above said combustion chamber, walls forming a pocket in open communication with said expansion 30 chamber, said pocket being so placed that said walls are heated by said burner, walls forming an exit opening in one side of said expansion chamber near the top thereof, and walls forming an inverted U-shaped passage 35 extending from the top of said combustion chamber up one side, across the top, and down the other side of said expansion chamber and delivering said products of combustion to the lower portion of said expansion 40 chamber.

In testimony whereof, I have hereunto set my hand at Los Angeles, California, this 21st day of November, 1919.

THOMAS J. POTTER.
